UNITED STATES PATENT OFFICE.

JOHN H. VAILE, OF DAYTON, OHIO.

PROCESS OF ACTUATING HYDROSTATIC PRESSES.

SPECIFICATION forming part of Letters Patent No. 416,020, dated November 26, 1889.

Application filed December 24, 1888. Renewed November 2, 1889. Serial No. 328,981. (No model.)

To all whom it may concern:

Be it known that I, JOHN H. VAILE, a citizen of the United States, residing at Dayton, in the county of Montgomery and State of

5 Ohio, have invented certain new and useful Improvements in the Process of Actuating Hydrostatic Presses, of which the following is a full, clear, and exact description, reference being had to the accompanying drawings, forming part of this specification.

My invention relates to all classes of presses wherein a liquid is used to exert the pressure; and, as coming primarily within the object of my invention, it relates to hydrostatic 15 presses for compressing substances of a very soft or plastic nature—such as lard, paraffine, and the like—and more particularly for expressing oil from meal, seeds, or other oleaginous substances.

20 It has for its object an improved process of actuating such presses, in which the press is at first supplied with a rapid but decreasing pressure, then with a slow and gradually-increasing pressure, both of said pressures coming from a low-pressure source, and, finally, 25 with a maximum pressure from an independent high-pressure source, all for a purpose to be hereinafter more fully explained.

My improved process is independent of any 30 particular apparatus for carrying it out, and the latter may be varied without departing from my invention.

In the accompanying drawings I have illustrated one form and arrangement of apparatus 35 suitable for the purpose, in which drawings—

Figure 1, Sheet 1, is an elevation, partly in section, of so much of the apparatus as is necessary to illustrate my invention. Fig. 2, 40 Sheet 1, is a modified form of the variable accumulator embodied in the apparatus shown in Fig. 1. Fig. 3, Sheet 2, is an enlarged sectional elevation of the valve mechanism embodied in the construction shown in Fig. 1.

45 The same letters of reference are used to indicate identical parts in all the figures.

In the apparatus illustrated in the drawings, A and B are two pumps—in this instance steam-pumps—of the usual or any 50 suitable construction, pumping from a supply-tank C, containing the liquid—usually oil—for actuating the press.

D is the cylinder of a hydrostatic press, of the usual or any suitable construction, and E its piston, to which the press-platen (not here 55 shown) is secured.

F is a strong air-tight vessel, which I designate a "variable accumulator," and into which the pump B pumps through a pipe G, provided with a check or other valve a. A 60 pipe b connects the accumulator F with the press-cylinder, and in this pipe is interposed the valve mechanism shown enlarged in Fig. 3 where H is a casing having at one side an inlet-port c, into which the pipe b from the 65 accumulator enters, and an outlet-port d at the other side, with which the branch of the pipe b between the press and valve connects. Any suitable check-valve e is seated in and controls a passage f between the ports c and 70 d. Any suitable valve g controls the port c to open and close it, and in this instance the valve is operated by a gear-wheel h, with a square bore loose on the squared upper end of the valve-stem and meshing with a similar gear-wheel i upon a valve j, which controls a supplemental port k. The valve j is provided with a crank l, and by this arrangement whenever the valve g is opened the valve j is closed, and vice versa. The port k 80 communicates with a discharge-pipe m, leading back to the supply-tank C.

Upon the top of the casing H are two uprights I, having at their upper ends a cross-head J, in which is guided the upper end of a 85 plunger-cylinder K, whose lower end is fitted over and packed upon a nozzle n, having an opening through it communicating with the port k. The lower flanged end of the plunger has secured to it a valve-stem o, passed with 90 proper packing down into the casing H—in this instance through the port d and through a supplemental port p, communicating with the port d—and has attached to its lower end a valve q, which is seated in a passage between 95 the port p and an inlet-port r, with which a pipe S from the pump A communicates. The port p communicates by a passage t, controlled by a hand-valve L, with a pipe u', leading back to the supply-tank C. A spiral 100 spring u surrounds the plunger K, and is confined between its lower flanged end and the cross-head J. The stem o is made sufficiently small so as to not close or interfere with the.

ports *d p*, and the valve *q* may be a check-valve held down to its seat by the stem *o*. The spring *u* may be provided with any suitable tension-regulating device. The ports *k* and *d* are connected by a small passage *w*.

When the apparatus is not in use, the valves *j* and *L* may be open and all the others should be closed.

M and *N*, Fig. 1, are the steam-supply pipes for the pumps, and they are provided, preferably, with reducing-valves *O*, which I have illustrated as of the well-known Mason type, whose particular construction forms no part of my invention; or any other suitable means for limiting the pressure of the pumps may be employed, such as safety-valves in the liquid part of the pump; or where power-pumps are used governors for regulating their speed may be used and controlled by the resistance.

The pump *A* is a high-pressure pump adjusted, for illustration of the operation of the apparatus, to a constant duty, say, of four thousand pounds, while the pump *B* is a low-pressure pump adjusted, for illustration of the operation, to a duty, for instance, that cannot exceed seven hundred pounds. The tension of the spring *u* is sufficient to overcome a pressure of four thousand pounds exerted on the under side of the valve *q*, combined with a pressure of slightly less than seven hundred pounds exerted on the plunger *K* through the nozzle *n*. The accumulator *F* is about two-thirds filled with oil or other pressure fluid, and the tank *C* is also supplied with oil.

Supposing that the material in the press is oil-meal, cotton, or linseed applied in layers in the usual way, and the operation of pressing the oil is ready to be begun for the first time, steam is admitted to both pumps. The pipe *S* of the pump *A* being closed by its valve *q* at a pressure of the spring *u*, which cannot be overcome by the pressure from the pump *A* acting on the under side of the valve *q* alone, said pump remains stationary, while the pump *B* begins pumping from the tank *C* into the accumulator *F*, gradually filling said accumulator and compressing the air therein until an indicator *P* shows the internal pressure to be seven hundred pounds. This point being reached, the pump *B* stops, because, as before explained, it is so adjusted that it cannot overcome a greater resistance. The attendant now closes the valves *L* and *j* and opens the valve *g*. The oil at once rushes through the pipe *b*, port *c*, and passage *f*, lifts the check-valve *e*, and passes on through the port *d* and pipe *b* into the press-cylinder *D* and raises the platen rapidly, but with a pressure constantly decreasing, as hereinafter explained, so that by the time working contact is made the pressure is only just sufficient to express the free and easily-expressed oil without bursting the bags and squeezing out the meal, and the further gradual increase of pressure is so regulated

that this safe condition is maintained as the oil exudes. The position of the valve parts at this stage of the operation is shown in Fig. 70

3. When the valve *g* is opened and the liquid in the accumulator escapes through the pipe *b* to the press, the pressure in the accumulator is rapidly decreased, so that, while the platen of the press is quickly forced up when it comes into working contact with the meal, it is with a decreasing pressure of considerably less than seven hundred pounds. As the pressure in the accumulator decreases, however, the pump *B* begins to work again and gradually restores the pressure to about that degree, so that after the short time in which the press exerts only a slight pressure on the meal it begins to increase until it gradually reaches a degree of nearly seven hundred pounds, whereupon the oil which has passed through the passage *w* and nozzle *n*, aided by that under pressure from the pump *A*, exerted on the valve *q* through the pipe *S* and port *r*, overcomes the resistance of the spring *u* and lifts the plunger *K*, thereby opening the valve *q* and permitting the inflow of oil from the pump *A* through the ports *r*, *p*, and *d* at a pressure at or quickly increasing to four thousand pounds. This sudden increase of back-pressure at once closes the check *e*, and the press with its now condensed meal continues to work at a pressure of four thousand pounds, the valve *q* being held open by this high pressure exerted on the plunger *K* through the passage *w*, port *k*, and nozzle *n*. After the check-valve *e* is closed the pump *B* continues to work, as before described, until a pressure of seven hundred pounds has been re-established in the accumulator, when it again stops, though the pump *A* continues its work. When the oil is entirely expressed, the attendant closes the valve *g* and opens the valves *j* and *L*, whereupon the oil in the plunger *K* and nozzle *n* at once escapes with that in the port *k* through the pipe *m* to the tank *C*, and the valve *q* is thereupon instantly closed by its spring *u*, the oil in the press-cylinder simultaneously escaping through the ports *d p t* and pipe *u'* to the tank *C*. The press may be at once filled with fresh meal and restarted, for after the first operation the accumulator *F* is always charged, as before explained. In this way I can control the action of the press and get the best results, no matter how unskilled the attendant may be, for there can be no overpressure given at first, which might burst the bags and squeeze out the meal, but, on the contrary, the action of the press is at first rapid, with a decreasing low pressure until working contact is made, after which the pressure steadily and gradually increases as the meal is condensed and the surplus oil expressed, and it is then automatically put under the maximum pressure.

In Fig. 2 I have shown another form of variable accumulator, where *Q* is a cylinder with a packed piston *R*, having at its top a cross-

head S, with pendent arms T, carrying at their bottom the constant weights U, above which are arranged a series of pick-up weights V W. The liquid enters from the pump B through 5 the pipe a' and discharges into the port c through the pipe b'. As the piston R is raised, the resistance is first increased by picking up the weight V, and finally increased to the maximum by picking up the weights W, where- 10 upon the pump B stops. Upon opening the valve g the liquid escapes to the press, first with the maximum pressure of the accumu- 15 lator, and then with a decreasing pressure, as the pick-up weights are arrested by any suitable stops, as the shoulders c', as will be readily understood.

Instead of the pick-up weights, springs 20 might be applied to the piston R in a manner to exert a maximum pressure thereon when it is elevated, which pressure would decrease as 25 the piston descends and the tension of the springs is released.

While the above-described apparatus affords a suitable and practical means for carrying out my improved process, my invention 25 is not limited to such an apparatus. Again, even if the general construction and arrangement of the apparatus I have illustrated be employed, yet many modifications may be 30 made in it without departing from its general character, and in another application covering said apparatus and filed simultaneously herewith I have illustrated and described some of said modifications.

35 The apparatus illustrated in the drawings forms the subject-matter of a separate application filed December 24, 1888, Serial No.

294,479, and no claim thereto is made in this application.

Having thus fully described my invention, I 40 claim—

1. The herein-described process of actuating hydrostatic presses, consisting in applying first a rapid but decreasing pressure, and then gradually increasing the same from a 45 low-pressure source, and finally admitting a maximum pressure from an independent high-pressure source.

2. The herein-described process of actuating hydrostatic presses, consisting in applying first a rapid but decreasing pressure, and then gradually increasing the same from a 50 variable accumulator supplied from a low-pressure source, and finally admitting a maximum pressure from an independent high- 55 pressure source.

3. In the art of expressing oil from oleaginous substances in hydrostatic presses, the herein-described process of actuating such presses, consisting in applying first a rapid 60 but decreasing pressure to force the platen of the press into working contact with the substance to be pressed, then exerting a light but gradually-increasing pressure while the surplus oil is being rapidly expressed, all of 65 said pressures coming from a low-pressure source, and then applying to the press a maximum pressure from an independent high-pressure source, substantially as and for the purpose described.

JOHN H. VAILE.
